PHONETIC TYPEWRITING MACHINE

Joseph Lee Sweeney, New York, N. Y.

Application September 24, 1938, Serial No. 231,478

41 Claims. (Cl. 197—9)

This invention relates to typewriting machines, and more particularly to phonetic typewriting machines.

Shorthand typewriters have been constructed heretofore which rely largely for such efficiency as they achieve upon some system of code. In such machines, the type bars are provided with letters or characters, and single characters and arbitrary groups of characters or letters are used to represent the various letters and/or sounds of the spoken language. Such a system must be learned before the operation of the machine itself can be learned, which means an initial multiplication of work. Obviously, moreover, the written product of the machine can be intelligible only to such readers as are familiar with the particular system of code used. Both of these factors have heretofore been drawbacks to the successful development of shorthand typewriters.

It is one of the primary objects of this invention to provide a typewriter capable of writing at virtually the speed of the spoken language but whose product will be intelligible to the normal reader without the necessity of knowing any system of code.

Another object of the invention is to provide a typewriting machine with which any single syllable may be written phonetically with a single stroke on the keyboard.

A further object is to provide a keyboard for a typewriter with which the above objects may be accomplished with the fewest possible keys.

A still further object is to provide a simplified and quieter form of ribbon and inking mechanism for a typewriter.

A general object is to provide a new system of phonetic typewriting.

Many other objects and advantages of the invention will in part be obvious and will in part be pointed out during the course of the following description.

A primary purpose of the system of writing of the invention is to make it possible to reproduce any word in the English language quickly and easily in its phonetic form, with a minimum of characters and a minimum possibility of being mistaken for any other word. The first step in the development of this system is to break down all words to their component syllables.

Every syllable other than single vowels consists of one of the following three combinations: consonant-vowel, vowel-consonant, or consonant-vowel-consonant. The term "consonant" as used above includes consonantal sounds represented by a group of consonants such as "sh,"

known as a digraph, or "shv," known as a trigraph. Certain of these consonantal sounds may occur either initially or finally in a syllable, and others occur only initially but never finally, and vice versa.

Similarly the vowel sounds may preferably be reproduced largely by the use of vowel digraphs, rather than by using diacritical marks in conjunction with the single vowels or diphthongs used in etymological spelling.

The system of writing developed in accordance with this invention is based upon the above outlined discoveries and principles. It may be written with pen or pencil or may be printed on a typewriter. In order, however, to make the most of the advantages it affords, it has been found preferable to embody its essentials in the construction of a typewriting machine. The object of this machine, as indicated above, is to be able to print whole syllables at a single stroke on the keyboard. Further explanation of this system of writing, therefore, will be given in connection with the following description of a typewriter embodying the invention, which description is given as a non-limiting example in connection with the accompanying drawings, in which:

Figure 1 is a plan view of a phonetic typewriter constructed in accordance with the invention;

Figure 2 is a bottom view of the mechanism shown in Fig. 1;

Figure 3 is a longitudinal section on the line 3—3 in Fig. 1, looking in the direction of the arrows;

Figures 4 and 5 are partial sections on the lines 4—4 and 5—5, respectively, in Fig. 1, looking in the direction of the arrows;

Figures 6 and 7 are detail views partly in elevation and partly in section, showing the operation of a typical pair of keys and key levers with their common type bar; and

Figure 8 is a plan view of a modified form of keyboard which may be used with the typewriter, the characters on the type bars corresponding with the key designations.

The chassis frame of the machine comprises generally the two metal side pieces 11 and 12, bolted at 13 to top plate 10, also preferably of metal. Sides 11 and 12 include legs 14 and 15, which may be provided with rubber feet 16. The rest of the frame includes cross bar 17, which carries channel 18, and cross bar 19.

The key levers, identified by the general reference character 20, are all pivoted between spacers 22 on shaft 21, mounted in sides 11 and 12. Each of key levers 20 is provided with a coil spring 23

for returning it to normal rest position after operation, the other end of each spring being secured in channel 18. To maintain alignment of the key levers there is provided a comb 24, whose lower edge is bent to form a channel 25 carrying a stop pad 26 of felt or similar material. Comb 24 may be held in the frame by any suitable means such as tongues at the ends of channel portion 25, fitting into grooves in sides 11 and 12. It will be seen in Fig. 1 that the slots in comb 24 are necessarily somewhat irregularly staggered in order to fit properly the non-uniformly bent key levers 20.

Above the key levers there is provided a stop 27 of leather or other suitable material carried by a channel 28 mounted in the chassis by means such as brackets 29. Key levers 20 and their associated keys are arranged to operate in pairs as shown in Figs. 6 and 7 and described herein-after. Each pair of key levers is provided and operatively connected with one of type bars 31. Each type bar carries a pair of characters, one above the other as shown in Fig. 3, arranged to strike against platen 30 on shaft 32 and thus to print on movable paper tape 33.

The convenient arrangement of paper feed means will be more clearly seen by reference to Figs. 1-4. As will be explained herein-after, the machine is designed to print each syllable on a separate line of tape 33, and so the paper feed is designed to advance tape 33 one line each time any of the key levers are operated. Platen shaft 32 rotates with the platen in the chassis and has fixed thereto ratchet wheel 34, which is operated by pawl 35 in the following manner:

Pivoted on shaft 21 is a frame comprising side pieces 36 and 37, space bar 40, and torsion member 38, serving to communicate the action of each key as uniformly as possible to the paper feed mechanism herein-after described. Space bar 40 is preferably channel shaped to carry a buffer member 39 of fibre or other suitable material which bears against the lower edges of key levers 20. Side piece 36 is extended to form arm 41, at the end of which is secured one end of bell crank lever 42. The other end of lever 42 is pivoted to one end of link member 43, whose opposite end is pivoted to approximately the middle of curved lever 44, pivoted at 45 to side frame 12 and at its other end to pawl 35. Movement of lever 44 on pivot 45 is controlled by coil spring 46 fixed to stud 47 in side frame 12. The action of this assembly is as follows:

When the key levers are in normal rest position, pawl 35 is in advanced position. When a key is struck, depressing one of key levers 20, space bar 40 will likewise be depressed, causing arm 41 to rise, with a clockwise movement as viewed in Fig. 4. This motion causes the upper end of bell crank lever 42 to move similarly and thus operate through link 43 to draw lever 44 back against the pull of its spring 46. This in turn operates to retract pawl 35, and bring it into engagement with a different tooth on ratchet wheel 34. Then when the key is released and arm 41 returns to normal position, spring 46 operates to draw lever 44 forward to its normal position and thus forces pawl 35 to rotate ratchet wheel 34 and platen 30.

The movement of arm 41 and lever 42 is guided and controlled by a stud 48 in side frame 12, cooperating with slot 49 in arm 41 and lever 42. This arrangement acts as a stop to limit movement of the paper feed assembly. To insure the return of space bar 40 and arm 41 to normal

rest position after each stroke, there is provided a pair of coil springs 50 extending from pegs 51 to side pieces 36 and 37.

Paper tape 33 is fed from any convenient source of supply as a roll or a tray, not shown, and passes over idler rolls 52 on shaft 53 mounted in the chassis, over guide shield 54 and around the platen. Cooperating with the platen is a friction roll 55 of rubber or other suitable material, rotating freely on shaft 56 carried by bail member 57. Bail 57 may also carry a shield 58 over which tape 33 is guided off the platen and out of the machine.

The above mentioned means for holding and releasing the paper are more clearly seen in Figs. 2 and 3. Paper shield 54 is rockingly mounted on shaft 59 secured in the chassis frame. Mounted on shafts 53 and 59 is a spring 60 arranged normally to urge shield 54 and tape 33 against platen 30. Friction roll ball 57 is pivoted on shaft 53, and there is also mounted on shaft 53 a coil spring 61 arranged to apply torque through hook 62 to bail 57 and so to urge friction roll 55 against the platen. Thus in normal position, tape 33 is held against platen 30 by shield 54 and friction roll 55, and when the platen is rotated as described above, tape 33 is necessarily carried along with it and so fed through the machine.

When it is desired to release tape 33, this may be accomplished by merely rocking bail 57 on shaft 53 to draw roll 55 away from platen 30. In the view in Fig. 3, this would be in clockwise direction. One side of bail 57 is extended to form an arm 63 and shoulder 64. When bail 57 is rocked as described above, shoulder 64 moves upward against shield 54 and thus operates to rock it on shaft 59, causing the shield to release its pressure against the platen and paper. When bail 57 has moved sufficiently to release tape 33 completely, arm 63 strikes shaft 59 and so prevents further movement. When bail 57 is released, spring 61 causes it to return roll 55 against the platen, and spring 60 similarly causes shield 54 to return to its gripping position. Bail 57 may conveniently have formed thereon a serrated edge 65 to facilitate tearing off of tape 33 when it is desired to remove copy from the machine.

A novel form of ribbon and inking mechanism is most clearly seen in Figs. 1 and 5, and includes an endless ribbon 66, travelling on a track composed of studs 67, 68, and 69 and roller pulley 70. Studs 68 and 69 are carried by L-shaped plate 71 mounted on chassis plate 10. Stud 67 is carried by slide 72 mounted on plate 71 by means such as studs 73 in slots 74 and controlled by tension spring 75 whose other end is attached to a peg 76 on chassis plate 10. Roller 70 is mounted on an axle 77 carried by brackets 78 and 79 fixed on chassis frame 11.

The driving mechanism for ribbon 66 is such that roller 70 is caused to rotate by operation of space bar 40. Fixed to roller 70 is a gear 80. Riveted in bracket 79 is a stud 81 on which rotate a pair of bevel pinions 82 and 83 joined together in any suitable way as by a sleeve 84 to operate as a single gear. Pinion 82 meshes with gear 80, and pinion 83 meshes with another bevel pinion 85 fixed on platen shaft 32. Roller 70 is preferably covered with a pad 86 of felt or other absorbent material which serves as a reservoir for ink. It will be obvious from the above description that each time platen 30 is rotated by operation of space bar 40, roller 70 will be caused to rotate through operation of gears 80, 82, 83 and 85, and thus ribbon 66 will have imparted

thereto an endless movement. Also by impregnating pad 86 with ink, ribbon 66 may be kept inked by reason of its constant passing over this pad.

It should be pointed out that if desired, the above inking assembly may be dispensed with, and a conventional type of ribbon feed substituted therefor. Thus the construction of the machine is such that standard ribbon spools may be mounted on chassis plate 10 and driven by any means conventional in the typewriting machine art. It should be pointed out also that by reason of the above described assembly for operating the paper feed and the ribbon, there is achieved a simple and positive dwell or synchronized stopping of both platen and ribbon before and during the actual printing of any characters on the paper tape.

The action of the keys, key levers, and type bars will be more clearly seen by reference to Figs. 3, 6 and 7. As pointed out above, the keys are arranged in pairs. Fig. 3 shows in normal rest position the keys and key levers for "A" 87, "OO" 88, space key 89, "—" 90, "*" 91, and "T" 92. Type bar 93 carries the two characters "T" 94 and "*" 95. As shown in Fig. 2, each of key levers 20 is offset to a varying extent in order to allow for a uniform keyboard, but every pair of key levers is identical with every other pair in operation, as well as in construction if the offset portion is disregarded; and the connections from each pair to its respective type bar are the same. For the sake of simplicity, therefore, this construction and operation will be described for a single pair of keys and key levers with particular reference to Figs. 6 and 7.

Before proceeding with this explanation, the purpose of this key lever construction should be pointed out. One of the primary objects of the invention is to provide a machine capable of writing phonetically at substantially the speed of speech. One requirement, therefore, is that the machine should include sufficient characters to represent all sounds of the spoken language. The objective of speed, however, adds the corollary to this requirement that the number of keys must be kept to a minimum. The objective of writing whole syllables at a single stroke provides the requirement that the letters must be printed at varying distances from each other along the line. To this, however, the objective of easy reading adds the corollary that the lines should be as short as possible and hence that the type bars should occupy as narrow a space laterally as possible.

A solution to the above problems is the placing of two or more characters on each type bar, but this apparent solution introduces new complications. One of these is that no type bar can carry two letters which might have to appear in the same syllable, since obviously only one character of the two can be printed at a single stroke. This problem, however, is explained more fully in connection with the description hereinafter of the keyboard arrangement and writing system.

The immediate problem is that of means for shifting the type bars to print the various characters thereon. Obviously no conventional shift means could solve this problem, for such shift means provide only for shifting the entire case of the machine to print either all the top or all the bottom characters on the type bars, and not for shifting individual type bars. In order to realize the other objectives of this invention, it is necessary to make it possible to print simultane-

ously the top characters on some type bars and the bottom characters on others. The problem, therefore, is to provide automatic individual shift key means for each type bar.

5 The mechanism shown in Figs. 3, 6 and 7 provides a suitable and satisfactory means for meeting this problem. This particular mechanism is shown only by way of illustration of one operative construction, and various other ways of accomplishing the same result may be used without departing from the scope of this invention.

For the sake of convenience in description, it will be assumed that keys 96 and 97 are the keys bearing the letters "J" and "L", respectively, at the lefthand side of the keyboard in Fig. 1. The operation is the same for every other similar pair of keys. Keys 96 and 97 are provided with key levers 98 and 99, respectively, each operatively connected to a common type bar 100. The connecting means include a pair of bell crank levers 103 and 102, respectively, pivoted on a common shaft 101. Shaft 101 is common to the bell crank levers of all of key levers 20, as shown in Figs. 1 and 3. Type bar 100 carries the two characters, "J" 104 and "L" 105.

20 Bell crank lever 103 is pivoted to type bar 100 at 106. Its lower end is provided with a slot 107 to receive pivot pin 108 fixed in key lever 99. Bell crank lever 102 is similarly slotted at 109 to receive pivot pin 110 in key lever 98. These slots are provided to permit the necessary change of centers in the levers for the dual action of the type bar. The upper end of bell crank lever 102 carries a pin 111 sliding in slot 112 in type bar 100.

25 The operation of this mechanism is shown in Figs. 6 and 7. Normally the keys, key levers and type bar are in the position shown in Fig. 3. When it is desired to print the letter "L," key 97 is depressed, and this motion is transferred through key lever 99 and bell crank lever 103 and imparts a pushing motion to type bar 100. This causes the type bar to move forward in a horizontal plane along pin 111, which slides in slot 112, and to strike platen 30 as shown in Fig. 7, thus printing the lower type character 105. Key lever 98 and its associated members take no part in this movement except for the supporting action of pin 111.

30 When it is desired to print the letter "J," both keys 96 and 97 are depressed, this action being facilitated by providing means such as finger 113 on key lever 99, which is forced down by key 96 if that key alone is struck by the operator. Any 35 similar connection may be used such as a pin in key lever 98 resting on key lever 99. The effect of this joint movement of key levers 98 and 99 and their respective bell crank levers is to push type bar 100 forward in a diagonally downward plane and thus to print the upper type character 104, as shown in Fig. 6.

35 The purpose of the above mechanism should be clear when there is taken into account the fact that a primary object of the machine is speed of operation and compactness together with accuracy. It would be possible to make keys 96 and 97 of equal size without in any way altering the basic operation of the machine, but the effect of this would be to make the keyboard large and unwieldy for rapid work. Moreover, the difference in shape and height between keys 96 and 97 makes key 97 easily recognizable to the touch in operation.

40 Thus it will be seen that the result of the above

described mechanism is to provide automatic individual shift means for each individual type bar. So efficient is this shift means that it is possible to print simultaneously the top character on one type bar and the bottom character on an adjacent type bar, as, for example, the letters "PR" or "TH" as shown in Fig. 1.

The manner of arranging the letters on the keyboard of the present invention is of great importance to the operation of the machine, as is also the sequence in which the various letters are printed. In order to achieve most effectively the objective of being able to print with a single stroke any syllable in the English language, the letters must be arranged in particular groups and sequence in conjunction with the above described operating mechanism.

There should be an initial group, preferably at the left side of the keyboard, which should include separate keys for each of the eighteen phonetic consonants which may occur at the beginning of syllables. Moreover, these keys should be so arranged that they can be used in combination to write at one stroke all the consonantal digraphs and trigraphs which commonly occur at the beginning of syllables, viz:

bl, br, ch, dr, dw, fl, fr, gl, gr, hw, kl, kr, kw, pl, pr, sf, sh, shr, sk, scr, skw, sl, sm, sn, sp, spl, spr, st, str, sw, th, thr, thw, tr, and tw.

There should be a group of vowel keys, preferably in the center of the keyboard, and including separate keys for a, e, i, o, and u; also a separate key for "long a", "long e", and "oo". These separate keys should be so arranged that in combination they can be used to write at one stroke the diphthongs ou and oi, and the digraphs ai, au, iu, and oa.

There should be a final group, preferably at the right of the keyboard, which should include separate keys for the fourteen phonetic consonants which occur individually at the end of words and these separate keys should be so arranged that they can be used in combination to write at one stroke all the consonantal digraphs and trigraphs which commonly occur at the end of the words, viz:

bz, ch, dg, ds, dst, dth, dz, fs, ft, fts, gsz, kd, ks, kst, ks-th, kt, kts, lb, lbz, lch, ld, ldz, lf, lfs, lf-th, lg, lk, lks, lkt, lm, lmz, ln, lns, lnz, lp, lps, ls, lsh, lst, lt, lth, lts, lv, lvz, lz, mb, mbz, md, mp, mps, mpt, mt, mts, mz, nch, nd, ndz, ng, ngz, nk, nks, ns, nst, nt, nts, nz, ps, pt, pts, rb, rbz, rch, rd, rdz, rf, rfs, rg, rgz, rk, rks, rl, rlz, rm, rmz, rn, rnz, rp, rps, rs, rsh, rst, rt, rth, rts, rv, rvz, rz, sh, sht, sk, sks, sp, sps, st, sts, th, thz, ts, vd, vz.

The arrangement of letters on the keyboard shown in Fig. 1 is believed to fulfill the above requirement completely. As shown, this keyboard comprises three main groups of keys. The left-hand group is designed to be operated by the fingers of the left hand and to reproduce any consonantal sound which may appear initially in a syllable. It includes twenty keys arranged in the order:

X	Z	CH	V	J
S	T	K	P	L
F	H	W	R	Y
D	G	B	M	N

writing from left to right across the paper tape 70 in the sequence:

X S F D Z T H G CH K W B V P R M J L Y N

The righthand group is designed to be operated by the fingers of the right hand and to reproduce

any final consonantal sound. It includes twenty keys arranged in the order:

KS	SH	V	CH	ST
R	N	D	F	TH
L	K	G	T	Z
S	M	P	B	S

writing in the sequence:

KS R L S SH N K M V D G P CH F T B ST TH Z S

The center group is designed to be operated by the thumbs of both hands and to reproduce any vowel sound and includes eight keys arranged in the order:

A	OO	E	EE
O	A	I	U

and writing in the sequence:

A O OO A E I E U

The center four keys shown in Fig. 1 are used for convenience and may be omitted without otherwise affecting the use of the machine. They include the characters "||", "*", and "—" and a space key, and the characters print on the tape in that sequence between the vowel sounds "A" and "E". That part of its type bar corresponding to the space key is blank.

It will be noted that two letters, namely "C" and "Q", are omitted, since neither appears in phonetic spelling, being reproduced by "k" or "s" and "kw", respectively. Ordinarily, the letter "X" would also be omitted in favor of "eks" or "ks", but by including it as shown, the machine is made capable of writing at a single stroke bisyllables like "expert" or "extract", which will be written "XPERT" and "XTRAKT".

It will be seen also that the letters are arranged to a great extent so that many common consonantal digraphs can be printed by keys operated by the same finger, that is, keys in the second and third lateral rows, counted from the top in Fig. 1, and the same row vertically. Examples are "TH", "KW", and "PR" in the left-hand group, and "RL", "NK", "FT" in the right-hand group. On the other hand, the letters are arranged so that it is never necessary for a finger to strike simultaneously keys in the second and bottom, or bottom two rows. It would be virtually impossible to achieve the former with any degree of speed or accuracy, and to do the latter would be merely to print the third row letter as explained above.

As was explained above in connection with Figs. 6 and 7, the two characters on each type bar print in the same vertical position on the tape, and only one can be printed at a time. Therefore, the letters should be so arranged on the keyboard that only one letter on each type bar will appear in any one syllable. In other words, if all the keys are struck simultaneously, only half of the letters will be printed. From this it will be seen that when the sequence is described above as "XSF D" etc., strict accuracy will change this to "X or S, F or D" etc. With this modification, however, the complete sequence 65 given above is correct.

In order to illustrate more clearly the operation of the invention, an example of its work will now be given. The following is a sentence as it is normally written: "All works of quality must bear a price in proportion to the skill, time, expense, and risk attending their invention and manufacture."

Transcribed phonetically according to the system of this invention, this sentence will read as follows: "Al works of kwality must bar a pris in

proporshun to the skil, tim, ekspens, and risk atending ther invenshun and manufakshur."

Written on the machine of this invention, this sentence will appear as follows:

W	O	R	L	K	S
KW	O	A	L	F	
T	M	Y	I		
B		U	S	T	
PR		A			
PR		I	S		
S	H	P	O	R	
T			U	N	
TH	K		E		
S	T		I	L	
X	P		E	M	
	R		A	N	D
T			I	S	K
TH			E	N	G
S	H	V	E	N	
M			A	N	D
F	S	H	A	U	K
			U	R	

It will be seen that each word is written according to its articulated sound—that is, as it should be pronounced. Where different vowels are used to represent supposedly identical sounds, as in "our," "e(a)rn" and "whirl"; "north" and "al(l)"; "polic(e)" and "se(a)l"; "ful(l)" and "stood"; "tru(e)," "who" and "food"; the vowels are written as they occur in the accepted etymological spelling, with the silent ones omitted.

Both vowels and consonants are omitted when silent. For this reason, certain words having different etymological spellings may be written alike, as will be noted in the examples of "lod(e)" and "lo(a)d," "p(i)er" and "pe(e)r"—the silent letter in each case being enclosed in parentheses.

When such words as these occur in actual usage their correct etymological meaning and spelling is indicated by their relation to the context. In oral speech the same reliance upon context is necessary. The context is no less a positive guide when words are written phonetically than when they are uttered orally. For convenience, however, the keyboard disclosed by this invention includes a "long a" and a "long e," and the vowels have been arranged in such sequence that any word, when standing alone, may be written so as to be clearly distinguishable from any other word which might be confused with it, thus:

The vowel digraph *au* may be used for the sound of *a* as in "ca(ugh)t," "ba(l)k," "ha(w)k," to distinguish these words from "cat," "ba(c)k," "ha(c)k." The vowel digraph *iu* may be used for the sound of "long *u*" as in "pur(e)," "tub(e)," "cut(e)," to distinguish these words from "pur(r)," "tub," "cut." The vowel digraph *yu* may be used for the "long *u*" at the beginning of such a word as "us(e)," thereby avoiding any conflict with "us." The vowel digraph *ai* may be used for the sound of *a* as in "a(i)r," "car(e)," "b(e)ar," to distinguish these words from "ar(e)," "car," "bar." The vowel digraph *oa* may be used for the sound of "long *o*" as in "o(a)r," "do(ugh)," "blo(a)t," to distinguish these words from "or," "do," "blot." The consonantal digraph *wr* may be used for the sound of *r* as in "(w)ring," "(w)rest," "(w)ro(ugh)t," to distinguish these words from "ring," "rest," "rot." The consonantal digraph *dg* may be used for the sound of "soft

"g" as in "ri(d)g(e)," "bu(d)g(e)," "do(d)g(e)," to distinguish these words from "rig," "bug," "dog." In no sense does this use of digraphs constitute what is commonly known as a "code."

5 On the contrary, their use is optional and when used they give a distinguishing characteristic to words that might otherwise be in conflict.

With the keyboard as shown the root form of any syllable or monosyllable in the English lan-

10 guage may be written in a single stroke according to the phonetic spelling or pronunciation given it in either Webster's or Funk & Wagnalls' dictionaries. The term "root form" is used to mean the elementary form of a syllable without

15 any change of ending. For example, in "be-que(a)th(e)d" the root forms of the two syllables are "be" and "que(a)th." In writing a few past tenses such as "ju(d)g(e)d," the root form of which is "ju(d)g(e)," the final *d* may be printed

20 by a second stroke, indicated arbitrarily, or left to be indicated by the context. Such cases, however, are comparatively rare.

It is believed that the general operation of the machine shown in Fig. 1 will be clear from the

25 above description and examples. There are, however, various modifications of the illustrated keyboard which will adapt the machine more advantageously to different types of work. One which will naturally come to mind is the provision of means for writing numerals.

With the keyboard shown in Fig. 1, numbers must be written out like other words. However, on this keyboard the top row of consonants, namely X, Z, CH, V, J, KS, SH, V, CH, and ST, 35 is included primarily for convenience. They are not essential to the accomplishment of any objective other than speed, and their contribution to the latter is relatively small. The bottom three rows of consonants together with the eight vowel keys will generally be sufficient for all ordinary writing needs.

40 This makes it possible to remove the top row of consonants and substitute numerals therefor. All that is required is the substitution in any convenient order on the keyboard and in the proper places on the type bars of the numerals 1-9 and 0 for the consonants. The logical order would be 1 for X, 2 for Z, and so forth, as shown in Fig. 8, but obviously any other sequence might be used.

50 No special provision has been made for indicating punctuation marks other than the characters "!", "*" and "-". These may be adapted in various ways, or punctuation may be left to be drawn from the context. Another way of

55 treating this problem is to use an arbitrary group of letters to indicate various punctuation marks. Such a group would ordinarily comprise two or more adjacent keys, as for example, "GTZ" for a comma and "PBS" for a period. By the use of 60 similar arbitrary groups to represent other letters, the machine may be converted into a code shorthand typewriter.

65 It will be seen, therefore, that the invention may take many forms which embrace the same principle, and it will be understood that the present invention is not limited, necessarily, to the precise details of the steps, manipulations, and structure, as are herein specifically illustrated and described, but it will be apparent that such details are subject to various modifications which will become apparent readily to one skilled in the art, without departing from the spirit of the invention; and it will be understood, therefore, that it is intended and desired to include within the 70 scope of the invention such modifications and

changes as may be necessary to adapt it to varying conditions and uses.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. In a typewriting machine having a frame and a platen, a pair of levers pivotally mounted on said frame, a type bar having a plurality of characters thereon operatively supported by certain ends of said levers, one of said levers being connected to said type bar by a lost-motion connection, and means operatively connected with the opposite ends of said levers to cause rotation of the other lever about its pivot to move said type bar to press one of said characters against said platen and rotation of both levers about their pivots to move said type bar to press another of said characters against said platen. 20

2. In a typewriting machine, a type bar, a pair of characters carried one above the other by said type bar, a key and key bar corresponding to each of said characters, said key bars being pivotally and coaxially mounted in said machine, and means for operatively connecting said key bars and said type bar, said means comprising a bell crank lever pivotally connected to one of said key bars and said type bar and a second bell crank lever pivotally connected to the other of said key bars and slidably and pivotally connected to said type bar, said levers being pivotally and coaxially mounted in said machine. 30

3. In a phonetic typewriting machine a plurality of types including the characters

X S F D Z T H G CH K W B V P R M J L Y N 40

arranged in pairs to print alternative characters from left to right in the sequence: X or S, F or D, Z or T, H or G, CH or K, W or B, V or P, R or M, J or L, Y or N, and means for mounting and actuating said types for printing selectively from a type of one or more of said pairs, whereby initial consonantal sounds of a syllable may be printed phonetically at a single stroke. 45

4. In a phonetic typewriting machine a plurality of types including the characters

Ā O OO A E I Ē U

arranged in pairs for printing alternative characters from left to right in the sequence: Ā or O, OO or A, E or I, Ē or U, and means for mounting and actuating said types for printing selectively from a type of one or more of said pairs whereby the vowel sound of a syllable may be printed at a single stroke. 55

5. In a phonetic typewriting machine a plurality of types including the characters

KS R L S SH N K M V D G P CH F T B ST TH Z S

arranged in pairs to print alternative characters from left to right in the sequence: KS or R, L or S, SH or N, K or M, V or D, G or P, CH or F, T or B, ST or TH, Z or S, and means for mounting and actuating said types for printing selectively from a type of one or more of said pairs, whereby final consonantal sounds may be printed phonetically at a single stroke. 65

6. In a phonetic typewriting machine, a keyboard comprising a group of keys, each key rep-

resenting a character, said keys being arranged in the order

1	2	3	4	5
S	T	K	P	L
F	H	W	R	Y
D	G	B	M	N

a plurality of type bars operatively connected with said keys having the said printing characters thereon, said type bars being arranged in said machine, so that reading from left to right, B, F, G, K and P will print before L and R; S will print before T, F, H, K, P, L, W, M, and N; T will print before H, R, W, and M; D will print before R and W; W will print before R; and G, H and K will print before W for printing phonetically the initial consonantal sound of a syllable; a second group of keys, each key representing a character, said keys being arranged in the order

Ā	OO	E	Ē
O	A	I	U

a plurality of type bars operatively connected with said keys and having the said printing characters thereon, said type bars being arranged so that reading from left to right, O will print before A, I, and U; A will print before I and U; and I will print before U, for printing the vowel sound of a syllable; and a third group of keys, each key representing a character, said keys being arranged in the order

6	7	8	9	0
R	N	D	F	TH
L	K	G	T	Z
S	M	P	B	S

a plurality of type bars operatively connected with said keys and having said printing characters thereon, said type bars being arranged in said machine so that, reading from left to right, R will print before L; both R and L will print before N, K, M, D, F, P, B, G, TH, T, Z, and the second S; the first S will print before K, M, D, P, T, and the second S; N will print before K, D, G, TH, T, Z, and the second S; K will print before D, T, and the second S; M will print before D, P, T, Z, and the second S; D will print before G, TH, Z, and the second S; F will print before TH, T, and the second S; P will print before T and the second S; G will print before TH; B, G, and TH will print before Z and the second S; and T will print before the second S; for printing the final consonantal sound of a syllable, said groups of type bars being arranged to print in left-to-right sequence.

7. In a phonetic typewriting machine a keyboard including a group of keys representing letters and arranged in the order

S	T	K	P	L
F	H	W	R	Y
D	G	B	M	N

a plurality of types corresponding to the said letters, certain of said types being arranged singly and certain other of said types being arranged in pairs, means including certain of said keys for mounting and actuating said single types for printing selectively from one or more thereof, and means including the remainder of said keys for mounting and actuating said pairs of types for printing selectively from a type of one or more of said pairs, all of said types being arranged to print the said characters from left to right in the sequence: S, F or D, T, H or G, K, W or B, P, R or M, L, Y or N, whereby the initial

consonantal sound of a syllable may be printed at a single stroke.

8. In a phonetic typewriting machine a keyboard including a group of keys representing letters or groups of letters and arranged in the order

R	N	D	F	TH
L	K	G	T	Z
S	M	P	B	S

a plurality of types corresponding to the said letters, certain of said types being arranged singly and certain other of said types being arranged in pairs, means including certain of said keys for mounting and actuating said single types for printing selectively from one or more thereof, and means including the remainder of said keys for mounting and actuating said pairs of types for printing selectively from a type of one or more of said pairs, all of said types being arranged to print the said letters from left to right in the sequence: R, L or S, N, K or M, D, G or P, F, T or B, TH, Z or S, whereby the final consonantal sound of a syllable may be printed at a single stroke.

9. In a phonetic typewriting machine a keyboard including a group of keys representing letters or groups of letters and arranged in the order

X	Z	CH	V	J
S	T	K	P	L
F	H	W	R	Y
D	G	B	M	N

a plurality of types corresponding to the said letters and arranged in pairs for printing alternative characters from left to right in the sequence: X or S, F or D, Z or T, H or G, CH or K, W or B, V or P, R or M, J or L, Y or N, and means including said keys for mounting and actuating said types for printing selectively from a type of one or more of said pairs, whereby the initial consonantal sound of a syllable may be printed at a single stroke.

10. In a phonetic typewriting machine a keyboard including a group of keys representing letters or groups of letters and arranged in the order

Ā	OO	E	Ē
O	A	I	U

a plurality of types corresponding to the said letters and arranged in pairs for printing alternative letters from left to right in the sequence: Ā or O, OO or A, E or I, Ē or U, and means including said keys for mounting and actuating said types for printing selectively from a type of one or more of said pairs, whereby the vowel sound of a syllable may be printed at a single stroke.

11. In a phonetic typewriting machine a keyboard including a group of keys representing letters and groups of letters and arranged in the order

KS	SH	V	CH	ST
R	N	D	F	TH
L	K	G	T	Z
S	M	P	B	S

a plurality of types corresponding to said letters and arranged in pairs for printing alternative characters from left to right in the sequence: KS or R, L or S, SH or N, K or M, V or D, G or P, CH or F, T or B, ST or TH, Z or S, and means including said keys for mounting and actuating said types for printing selectively from a type of one or more of said pairs, whereby the final consonantal sound of a syllable may be printed at a single stroke.

12. In a phonetic typewriting machine, a keyboard including a group of keys representing letters and arranged in the order

S	T	K	P	L
F	H	W	R	Y
D	G	B	M	N

a plurality of type bars operatively connected to said keys and having the said letters thereon, there being a separate type bar for each of the letters S T K P L, and a separate type bar for each pair of letters FD, HG, WB, RM, and YN, the said type bars being arranged in said machine so that reading from left to right B, F, G, K, P, will print before L and R; S will print before T, F, H, K, P, L, W, M, and N; T will print before H, R, W, and M; D will print before R and W; W will print before R; and G, H, and K will print before W for printing the initial consonantal sound of a syllable, said type bars being mounted for individual operation or simultaneous operation of two or more type bars.

13. In a phonetic typewriting machine including a platen, a plurality of type bars, means to mount said type bars for independent movement

against said platen to permit simultaneous striking of any number of type bars against said platen, separate means to move said type bars individually, a pair of characters on each of certain of said type bars, and means associated with said last mentioned means to predetermine which of said characters will print when said type bar is moved against said platen, the said pairs of characters being FD, HG, WB, RM, YN, LS, KM, GP, TB, ZS, AO, OOA, EI, EU, whereby it will never be necessary to print both characters of a pair to produce a representation of a phonetic syllable in the language with which the typewriting machine is designed to be used.

14. In a typewriting machine for phonetically printing one or more syllables of the English language at a single stroke and including a platen, a plurality of type bars, means to mount said type bars for independent movement against said platen, permitting simultaneous striking of any number of type bars against said platen, separate means to move said type bars individually, a pair of characters or groups of characters on each of said type bars, means associated with

said last mentioned means to predetermine which of a pair of characters will print when the type bar carrying the pair is moved against said platen, said pairs of characters including XS, ZT, CH K, VP, JL, KS R, SH N, VD, CH F, ST TH, FD, HG, WB, RM, YN, LS, KM, GP, TB, ZS, AO, OO A, EI, and ĒU.

15. In a phonetic typewriting machine, a keyboard comprising a group of keys, each key representing a character, said keys being arranged in the order

S	T	K	P	L
F	H	W	R	Y
D	G	B	M	N

a plurality of type bars operatively connected with said keys having the said printing characters thereon, certain of said type bars having single characters thereon and certain of said type bars having pairs of characters thereon, said type bars being arranged in said machine so that reading from left to right B, F, G, K, and P will print before L and R; S will print before T, F, H, K, P, L, W, M, and N; T will print before H, R, W, and M; D will print before R and W; W will print before R; and G, H, and K will print before W for printing phonetically the initial consonantal sound of a syllable; a second group of

keys, each key representing a character, said keys being arranged in the order

$\overline{A}$ OO E $\overline{E}$
O A I U

a plurality of type bars operatively connected with said keys and having the said printing characters thereon, said type bars being arranged in said machine so that reading from left to right O will print before A, I, and U; A will print before I and U; and I will print before U, for printing the vowel sound of a syllable; and a third group of keys each key representing a character, said keys being arranged in the order

R N D F TH
L K G T Z
S M P B S

a plurality of type bars operatively connected with said keys and having said printing characters thereon, said type bars being arranged in said machine so that, reading from left to right, R will print before L; both R and L will print before N, K, M, D, F, P, SH, B, G, TH, T, Z, CH, ST, and the second S; the first S will print before K, M, D, P, T, and the second S; N will print before K, D, G, TH, T, Z, and the second S; P will print before D, T, and the second S; SH will print before T, Z, and the second S; B will print before G, TH, Z, and the second S; G will print before TH and T; CH, B, and TH will print before Z and the second S; G will print before TH, and ST; and T will print before the second S, for printing the final consonantal sound of a syllable, said groups of type bars being arranged to print in left-to-right sequence.

16. In a phonetic typewriting machine, a keyboard comprising a group of keys, each key representing a character, said keys being arranged in the order

X Z CH V J
S T K P L
F H W R Y
D G B M N

a plurality of type bars operatively connected with said keys having the said printing characters thereon, said type bars being arranged in said machine so that reading from left to right B, F, G, K, and P will print before L and R; S will print before T, F, H, K, P, L, W, M, and N; T will print before H, R, W, and M; D will print before R, and W; G, H, and K will print before W; Z will print before L, V, and W; and W will print before R, for printing phonetically the initial consonantal sound of a syllable; a second group of keys each key representing a character, said keys being arranged in the order

$\overline{A}$ OO E $\overline{E}$
O A I U

a plurality of type bars operatively connected with said keys and having the said printing characters thereon, said type bars being arranged in said machine so that reading from left to right O will print before A, I, and U; A will print before I and U; and I will print before U, for printing the vowel sound of a syllable; and a third group of keys each key representing a character, said keys being arranged in the order

KS SH V CH ST
R N D F TH
L K G T Z
S M P B S

a plurality of type bars operatively connected with said keys and having said printing characters thereon, said type bars being arranged for printing said characters from left to right in

said machine so that, reading from left to right, R will print before L; both R and L will print before N, K, M, V, D, F, P, SH, B, G, TH, T, Z, CH, ST, and the second S; the first S will print

5 before K, M, D, P, T, and the second S; N will print before K, D, G, TH, T, Z, CH, ST, and the second S; P will print before D, T, and the second S; SH will print before T, Z, and the second S; KS will print before TH and T; G, CH, B, and TH will print before Z and the second S; G will print before TH, and ST; and T will print before the second S, for printing the final consonantal sound of a syllable, said groups of type bars being arranged to print in left-to-right sequence.

17. In a phonetic typewriting machine a keyboard comprising a group of keys, each key representing a character, said keys being arranged in three groups in the order

X Z CH V J KS SH V CH ST
S T K P L R N D F TH
F H W R Y L K G T Z
D G B M N S M P B S

$\overline{A}$ OO E $\overline{E}$
O A I U

a plurality of type bars operatively connected with said keys having the said printing characters thereon, said type bars being arranged in said machine so that reading from left to right B, F, G, K, and P will print before L and R; S will print before T, F, H, K, P, L, W, M, and N;

35 T will print before H, R, W, and M; D will print before R and W; G, H, and K will print before W; Z will print before L, V, and W; and W will print before R in the first group; O will print before A, I, and U; A will print before I and U; and I will print before U in the second group; R will print before L; both R and L will print before N, K, M, V, D, F, P, SH, B, G, TH, T, Z, CH, ST, and the second S; the first S will print before K, M, D, P, T, and the second S; N will print before

40 K, D, G, TH, T, Z, CH, ST, and the second S; P will print before D, T, and the second S; M will print before D, P, T, Z, and the second S; V will print before Z and the second S; D will print before G, TH, Z, ST, and the second S; F will print before TH, T, and the second S; P will print before T, Z, and the second S; SH will print before T, Z, and the second S; KS will print before TH and T; G, CH, B, and TH will print before Z and the second S; G will print before TH

45 and ST; and T will print before the second S in the third group, said first, second, and third groups of types being arranged to print from left to right for printing phonetically the initial consonantal sound of a syllable, the vowel sound, and the final consonantal sound.

50 18. In a phonetic typewriting machine a keyboard comprising a group of keys, each key representing a character, said keys being arranged in three groups in the order

S T K P L R N D F TH
F H W R Y L K G T Z
D G B M N S M P B S

$\overline{A}$ OO E $\overline{E}$
O A I U

70 a plurality of type bars operatively connected with said keys having the said printing characters thereon, said type bars being arranged in said machine so that reading from left to right in the first group, B, F, G, K, and P will print before L and R; S will print before T, F, H, K, P, L,

W, M, and N; T will print before H, R, W, and M; D will print before R and W; W will print before R; G, H, and K will print before W; reading from left to right in the second group, O will print before A, I, and U; A will print before I and U; and I will print before U; reading from left to right in the third group, R will print before L; both R and L will print before N, K, M, D, F, P, B, G, TH, T, Z, and the second S; the first S will print before K, M, D, P, T, and the second S; N will print before K, D, G, TH, T, Z, and the second S; K will print before D, T, and the second S; M will print before D, P, T, Z, and the second S; D will print before G, TH, Z, and the second S; F will print before TH, T, and the second S; P will print before T and the second S; G will print before TH; B, G, and TH will print before Z and the second S; and T will print before the second S; said first, second, and third groups of types being arranged to print from left to right for printing phonetically the initial consonantal sound of a syllable, the vowel sound, and the final consonantal sound.

19. In a phonetic typewriting machine, a keyboard including a group of keys representing letters and arranged in the order

R	N	D	F	TH
L	K	G	T	Z
S	M	P	B	S

a plurality of type bars operatively connected to said keys and having the said letters thereon, there being a separate type bar for each of the letters R, N, D, F, TH, and a separate type bar for each pair of letters LS, KM, GP, TB, and ZS, the said type bars being arranged in said machine so that, reading from left to right, R will print before L; R and L will print before N, K, M, D, F, B, P, G, TH, T, Z, and the second S; the first S will print before K, M, D, P, T, and the second S; N will print before K, D, G, TH, T, Z, and the second S; K will print before D, T, and the second S; M will print before D, P, T, Z, and the second S; D will print before G, TH, Z, and the second S; F will print before TH, T, and the second S; P will print before T and the second S; G will print before TH; B, G, and TH will print before Z and the second S; and T will print before the second S, for printing the final consonantal sound of a syllable, said type bars being mounted for individual operation or simultaneous operation of two or more type bars.

20. In a phonetic typewriting machine, a keyboard including two groups of keys representing letters and arranged in the order

S	T	K	P	L	R	N	D	F	TH
F	H	W	R	Y	L	K	G	T	Z
D	G	B	M	N	S	M	P	B	S

a plurality of type bars operatively connected to said keys and having the said letters thereon, there being a separate type bar for each of the letters S, T, K, P, L, R, N, D, F, TH, and a separate type bar for each pair of letters FD, HG, WB, RM, YN, LS, KM, GP, TB, and ZS, the said type bars being arranged in said machine so that, reading from left to right, B, F, G, K, and P will print before L and R; S will print before T, F, H, K, P, L, W, M, and N; T will print before H, R, W, and M; D will print before R and W; W will print before R; G, H, and K will print before W, in the first group; R will print before L; both R and L will print before N, K, M, D, F, P, B, G, TH, T, Z, and the second S; the first S will print before K, M, D, P, T, and the second S; N will print before K, D, G, TH, T, Z, and the second S; K will print before D, T, and the second S; M will

print before D, P, T, Z, and the second S; D will print before G, TH, Z, and the second S; F will print before TH, T, and the second S; P will print before T and the second S; G will print before TH; B, G, and TH will print before Z and the second S; and T will print before the second S, in the second group; all of the type bars carrying the letters corresponding to the left group of keys printing to the left of those corresponding to the right group of keys, the left group of keys being used for printing the initial consonantal sound of a syllable, and the right group being used for printing the final consonantal sound of a syllable, said type bars being mounted for individual operation or simultaneous operation of two or more type bars.

21. In a phonetic typewriting machine a set of types, certain of said types being arranged singly and certain other of said types being arranged in pairs for printing alternative characters, all of said types being arranged to print characters from left to right in the sequence: S, E or D, T, H or G, K, W or B, P, R or M, L, Y or N, R, L or S, N, K or M, D, G or P, F, T or B, TH, Z or S, means for mounting and actuating said single types for printing selectively from one or more thereof, and means for mounting and actuating said pairs of types for printing selectively from a type of one or more of said pairs.

22. In a typewriting machine a frame, a pair of levers pivotally mounted on said frame, a type bar supported by said levers, a pair of characters on said type bar, one of said levers being pivotally attached to one end of said type bar, whereby rotation of said lever will cause movement of said type bar in a predetermined direction, a key operatively connected to said last mentioned lever to cause rotation thereof when said key is depressed, said other lever being connected to the said type bar with a lost-motion connection, said connection permitting limited movement of said type bar in said predetermined direction without movement of said other lever, whereby said other lever acts to guide the direction of movement of said type bar, a second key operatively connected to said other lever to cause rotation thereof when said second key is depressed, and means acting to depress said first key when said second key is depressed.

23. In a typewriting machine at least three keys arranged in a row from front to back with the finger engaging surfaces of said keys in substantially the same plane for manipulation with a single finger, a plurality of type elements, a plurality of type characters on one of said elements and at least one type character on another of said elements, means operatively connecting the two of said keys nearest the operator with said type element having the plurality of type characters thereon, said last mentioned means including means to move said type element when the key nearest the operator of said two keys is depressed, so as to print one of said type characters, means serving to condition said type element to print the other of said type characters when the other of said keys is depressed, and means to cause operation of said key nearest the operator when said other key is depressed but to permit said key nearest the operator to be depressed without operation of said other key, and means operatively to connect said third key with said type element having at least one type character thereon, whereby when all three keys are depressed simultaneously two of said type characters will print, when the two keys nearest the operator are de-

pressed one of the same characters will print, and when the key nearest the operator is alone depressed one different character will print.

24. In a phonetic typewriting machine a keyboard comprising a group of keys, each key representing a character, said keys being arranged from back to front of the machine in the order

X	Z	CH	V	J	KS	SH	V	CH	ST	
S	T	K	P	L	R	N	D	F	TH	
F	H	W	R	Y	L	K	G	T	Z	
D	G	B	M	N	S	M	P	B	S	
					A	OO	E	Ē		
					O	A	I	U		

the finger-engaging surfaces of the keys of the first four rows from back to front lying substantially in the same plane and those of the last two rows from back to front lying substantially in the same plane, the keys of the first, third, and fifth rows from back to front being enough smaller than the other keys to provide a greatly foreshortened keyboard while permitting said keys of the first, third, and fifth rows to be depressed simultaneously with keys of adjacent rows and each being operatively paired with the key immediately in front of it, a plurality of type bars each being operatively connected with a different pair of keys, a pair of types on each type bar corresponding to the characters represented by the keys operatively connected to said type bar, a platen, means mounting and connecting each type bar with its associated pair of keys so as to move said type bar to press one of said types against said platen when the forward key of said pair is depressed and to move said type bar to press the other of said types against said platen when both keys are depressed, said type bars being arranged to print selectively from alternative characters of one or more of said pairs in the sequence X or S, F or D, Z or T, H or G, CH or K, W or B, V or P, R or M, J or L, Y or N, Ā or O, OO or A, E or I, Ē or U, KS or R, L or S, SH or N, K or M, V or D, G or P, CH or F, T or B, ST or TH, Z or S, whereby the initial consonantal sound of a syllable, the vowel sound, and the final consonantal sound may be printed phonetically with a single stroke of the keys and with a minimum movement of the operator's fingers.

25. In a phonetic typewriting machine a keyboard comprising a group of keys, each key representing a letter or combination of letters, said keys being arranged from back to front of the machine in the order

X	Z	CH	V	J	KS	SH	V	CH	ST	
S	T	K	P	L	R	N	D	F	TH	
F	H	W	R	Y	L	K	G	T	Z	
D	G	B	M	N	S	M	P	B	S	
					A	OO	E	Ē		
					O	A	I	U		

the finger-engaging surfaces of the keys of the first four rows from back to front lying substantially in the same plane and those of the last two rows from back to front lying substantially in the same plane, the keys of the first, third, and fifth rows from back to front being enough smaller than the other keys to provide a greatly foreshortened keyboard while permitting said keys of the first, third, and fifth rows to be depressed simultaneously with keys of adjacent rows and each being operatively paired with the key immediately in front of it whereby the initial consonantal sound of a syllable, the vowel sound, and the final consonantal sound may be printed phonetically with a single stroke of the keys and with a minimum movement of the operator's fingers.

26. In a typewriting machine for printing a plurality of characters simultaneously, a keyboard comprising a plurality of closely positioned large and small keys arranged in rows with the 5 keys in one row aligned with the keys in the other rows and with their finger engaging surfaces lying in substantially the same plane, there being at least two large keys in front-to-back alignment with one small key, means to mount each 10 of said small keys in paired relation with a large key in front-to-back alignment with it, so as to cause a large key of a pair to be depressed when the small key is depressed but to permit said large key to be depressed independently of said small key, a plurality of types and means to couple operatively the keys of each pair to a pair of said types so as to print one character when the large key is depressed and to print another character when the pair of keys is depressed, the 15 small key of each pair being so small that under efficient operating conditions it cannot be conveniently depressed singly, thus permitting the keyboard to be greatly foreshortened but also permitting the small key of a pair to be depressed simultaneously with any adjacent key in front-to-back alignment and by means of a single finger.

27. In a phonetic typewriting machine a set of types for printing the initial consonantal sounds 30 of a syllable and comprising the type characters,

S F D T H G K W
B P R M L Y N

a plurality of type bars, each of which has at 35 least one of said type characters thereon and some of which have a pair of said type characters thereon, a plurality of main keys, means to connect each of said main keys with a type bar so as to cause said type bar to move in a predetermined direction to print one of said type characters carried thereby when said main key is depressed, a plurality of shift keys, each of said shift keys being closely associated with one of said main keys so that the shift key may be depressed simultaneously with its associated main key by a single finger, means connecting each shift key with the type bar connected to the associated main key to shift the direction of movement of the type bar when the shift key and its associated main key are simultaneously depressed whereby another type character on said type bar is printed, said type characters being arranged on said type bars and said type bars being arranged in the machine so that, reading from left to right, B, F, G, K, and P will print before L and R; S will print before T, F, H, K, P, L, W, M, and N; T will print before H, R, W, M; D will print before R and W; W will print before R; and G, H, and K will print before W.

28. In a phonetic typewriting machine a set of types including Ā, O, OO, A, E, I, Ē, and U, means to mount and actuate said types so that a plurality thereof may be simultaneously printed, said types being arranged in said machine so that reading from left to right, O will print before A, I, and U; A will print before I and U; and I will print before U.

29. In a phonetic typewriting machine a set of types for printing the initial consonantal sounds 70 of a syllable and including the characters R, L, a first S, N, K, M, D, G, P, F, T, B, TH, Z, and a second S, means to mount and actuate said types so that a plurality thereof may be simultaneously printed, said types being arranged in said machine so that, reading from left to right, R will

print before L; both R and L will print before N, K, M, D, F, P, B, G, TH, T, Z, and the second S; the first S will print before K, M, D, P, T, and the second S; N will print before K, D, G, TH, T, Z, and the second S; K will print before D, T, and the second S; M will print before D, P, T, Z, and the second S; D will print before G, TH, Z, and the second S; F will print before TH, T, and the second S; P will print before T and the second S; G will print before TH; B, G, and TH will print before Z and the second S; and T will print before the second S.

30. In a phonetic typewriting machine a set of types arranged in three groups and including the following characters: S, F, D, T, H, G, K, W, B, P, 15 R, M, L, Y, and N in the first group, Ā, O, OO, A, E, I, Ē, and U in the second group; and R, L, a first S, N, K, M, D, G, P, F, T, B, TH, Z, and a second S in the third group, means to mount and actuate said types so that a plurality thereof from each group may be printed simultaneously, said types being arranged in said machine so that, reading from left to right in the first group, B, F, G, K, and P will print before L and R; S will print before T, F, H, K, P, L, W, M, and N; T will print before H, R, W, and M; D will print before R and W; W will print before R; and G, H, and K will print before W; reading from left to right in the second group O will print before A, I, and U; A will print before I and U; and I will print before U; reading from left to right in the third group, R will print before L; both R and L will print before N, K, M, D, F, P, B, G, TH, T, Z and the second S; the first S will print before K, M, D, P, T, and the second S; N will print before K, D, G, TH, T, Z, and the second S; K will print before D, T, and the second S; M will print before D, P, T, Z, and the second S; D will print before G, TH, Z, and the second S; F will print before TH, T, and the second S; P will print before T and the second S; G will print before TH; B, G, and TH will print before Z and the second S; and T will print before the second S; said first, second, and third groups of types being arranged to print from left to right.

31. In a phonetic typewriting machine a set of types for printing the initial consonantal sounds of a syllable and comprising the type characters

X S F D Z T H G CH K W B V
P R M J L Y N

a plurality of type bars each having a pair of said type characters thereon, a plurality of main keys, means to connect each of said main keys with a type bar so as to cause said type bar to move in a predetermined direction to print one of said type characters carried thereby when said main key is depressed, a plurality of shift keys, each of said shift keys being closely associated with one of said main keys so that the shift key may be depressed simultaneously with its associated main key by a single finger, means connecting each shift key with the type bar connected to the associated main key to shift the direction of movement of the type bar when the shift key and its associated main key are simultaneously depressed whereby another type character on said type bar is printed, said type characters being so arranged on said type bars and said type bars being so arranged in the machine that, reading from left to right, B, F, G, K, and P will print before L and R; S will print before T, F, H, K, P, L, W, M, and N; T will print before H, R, W, and M; D will print before R and W;

G, H, and K will print before W; Z will print before L, V, and W; and W will print before R.

32. In a phonetic typewriting machine a set of types for printing the final consonantal sounds 5 of syllables and including the characters KS, R, L, a first S, SH, N, K, M, V, D, G, P, CH, F, T, B, ST, TH, Z, and a second S, means to mount and actuate said types so that a plurality of characters may be simultaneously printed, said types being arranged in said machine so that, reading from left to right, R will print before L, both R and L will print before N, K, M, V, D, F, P, SH, B, G, TH, T, Z, CH, ST, and the second S; the first S will print before K, M, D, P, T, and the second S; N will print before K, D, G, TH, T, Z, CH, ST, and the second S; K will print before D, T, and the second S; M will print before D, P, T, Z, and the second S; V will print before the second S and Z; D will print before G, TH, Z, ST, and the second S; F will print before TH, T, and the second S; P will print before T and the second S; SH will print before T, Z, and the second S; KS will print before TH and T; G, CH, B and TH will print before Z and the second S; G will print before TH and ST; and T will print before the second S.

33. In a phonetic typewriting machine a set of types arranged in three groups including the characters: S, F, D, Z, T, H, G, CH, K, W, B, V, 30 P, R, M, J, L, Y, and N in the first group, Ā, O, OO, A, E, I, Ē, and U in the second group, KS, R, L, a first S, SH, N, K, M, V, D, G, P, CH, F, T, B, ST, TH, Z, and a second S in the third group, means to mount and actuate said types so that a plurality of types from each group may be simultaneously printed, said types being arranged in said machine so that, reading from left to right, B, F, G, K, and P will print before L and R; S will print before T, F, H, K, P, L, W, M, and N; T will print before H, R, W, and M; D will print before R and W; G, H, and K will print before W; Z will print before L, V, and W; and W will print before R in the first group; O will print before A, I, and U; A will print before I and U; and I will print before U, in the second group; R will print before L, both R and L will print before N, K, M, V, D, F, P, SH, B, G, TH, T, Z, CH, ST, and the second S; the first S will print before K, M, D, P, T, and the second S; N will print before K, D, G, TH, T, Z, CH, ST, and the second S; K will print before D, T, and the second S; M will print before D, P, T, Z, and the second S; V will print before S and Z; D will print before G, TH, Z, ST, and the second S; F will print before TH, T, and the second S; P will print before T, Z, and the second S; SH will print before TH and T; G, CH, B and TH will print before Z and the second S; G will print before TH and ST; and T will print before the second S in the third group; said first, second, and third groups of types being arranged to print from left to right.

34. In a typewriting machine at least three keys arranged in a row from front to back of the 65 machine with the finger engaging surfaces of said keys in substantially the same plane for manipulation by a single finger, a plurality of type characters, means operatively connecting the rearmost key with one of said type characters to cause said type character to print when said rearmost key is depressed, means operatively connecting the foremost key with another of said type characters to cause the last mentioned type character to print when said foremost key is depressed, and means operatively connecting the

middle key with said last-mentioned connecting means to cause said foremost key associated with said last mentioned connecting means to be depressed when said middle key is depressed and to affect the operation of said last mentioned connecting means to print another of said type characters instead of the one normally printed when said foremost key is depressed, whereby two of said type characters will print when said three keys are simultaneously depressed, one of said same type characters will print when the two keys nearest the operator are simultaneously depressed, and a single different type character will print when the key nearest the operator is depressed alone.

35. In a typewriter for printing a plurality of characters simultaneously, a keyboard comprising a plurality of closely positioned depressible large and small keys arranged in a plurality of rows extending from front to back of said keyboard and with their finger engaging surfaces lying substantially in the same plane, each of said rows comprising at least one small key having a large key in front of it and a large key in back of it, means to mount said keys with a small key of each row in paired relation with one of the large keys of said row, a plurality of types arranged in pairs, means controlled by the large key of each pair to effect printing from one of a pair of types when said large key is depressed, means controlled jointly by the large and small keys of each pair to effect printing from the other of said pair of types when both keys of said pair are depressed, the small key of each pair being so small that under efficient operating conditions, it could not be conveniently depressed singly, thus permitting the keyboard to be greatly foreshortened, but also permitting the small key of each row to be depressed simultaneously with either large key of said row and by means of a single finger.

36. In a phonetic typewriting machine a set of types for printing consonantal characters both at the beginning of syllables before vowels and at the end of syllables after vowels, the types used at the beginning of syllables before vowels being S, F, D, Z, T, H, G, CH, K, W, B, V, P, R, M, J, L, Y, N, and those used at the end of syllables after vowels being KS, R, L, a first S, SH, N, K, M, V, D, G, P, CH, F, T, B, ST, TH, Z, and a second S, the said types used at the beginning of syllables before vowels being arranged in the said machine so that reading from left to right B, F, G, K, and P will print before L and R; S will print before T, F, H, K, P, L, W, M, and N; T will print before H, R, W, and M; D will print before R and W; G, H, and K will print before W; Z will print before L, V, and W; and W will print before R; the said types used at the end of syllables, after vowels, being arranged in said machine so that, reading from left to right, R will print before L; both R and L will print before N, K, M, V, D, F, P, SH, B, G, CH, ST, and the second S; the first S will print before K, M, D, P, T, and the second S; N will print before K, D, G, TH, T, Z, CH, ST, and the second S; K will print before D, T, and the second S; M will print before D, P, T, Z, and the second S; V will print before Z and the second S; D will print before G, TH, Z, ST, and the second S; F will print before TH, T, and the second S; P will print before T and the second S; SH will print before T, Z, and the second S; KS will print before TH and T; G, CH, B, and TH will print before Z and the second S; G will print before TH and ST; and T will print before the second S; and the said types for printing the vowels being arranged in said machine so that, reading from left to right, O will print before A, I, and U; A will print before I and U; and I will print before U; and means including a plurality of keys operatively connected to said types for mounting and actuating said types for printing selectively one or more of the said type characters, all of the types used at the beginning of syllables being mounted to print at the left of said vowel types and all of said vowel types being mounted to print at the left of those used at the end of syllables.

37. In a phonetic typewriting machine a set of types for printing consonantal characters both at the beginning of syllables before vowels and at the end of syllables after vowels, the types used at the beginning of syllables before vowels being S, F, D, Z, T, H, G, CH, K, W, B, V, P, R, M, J, L, Y, N, and those used at the end of syllables after vowels being KS, R, L, a first S, SH, N, K, M, V, D, G, P, CH, F, T, B, ST, TH, Z, and a second S, and those used for the vowels being Ā, O, OO, A, E, I, Ē, U, the said types used at the beginning of syllables before vowels being arranged in the said machine so that reading from left to right B, F, G, K, and P will print before L and R; S will print before T, F, H, K, P, L, W, M, and N; T will print before H, R, W, and M; D will print before R and W; G, H, and K will print before W; Z will print before L, V, and W; and W will print before R; the said types used at the end of syllables, after vowels, being arranged in said machine so that, reading from left to right, R will print before L; both R and L will print before N, K, M, V, D, F, P, SH, B, G, CH, ST, and the second S; the first S will print before K, M, D, P, T, and the second S; N will print before K, D, G, TH, T, Z, CH, ST, and the second S; K will print before D, T, and the second S; M will print before D, P, T, Z, and the second S; V will print before Z and the second S; D will print before G, TH, Z, ST, and the second S; F will print before TH, T, and the second S; P will print before T and the second S; SH will print before T, Z, and the second S; KS will print before TH and T; G, CH, B, and TH will print before Z and the second S; G will print before TH and ST; and T will print before the second S; and the said types for printing the vowels being arranged in said machine so that, reading from left to right, O will print before A, I, and U; A will print before I and U; and I will print before U; and means including a plurality of keys operatively connected to said types for mounting and actuating said types for printing selectively one or more of the said type characters, all of the types used at the beginning of syllables being mounted to print at the left of said vowel types and all of said vowel types being mounted to print at the left of those used at the end of syllables.

38. In a phonetic typewriting machine a set of types for printing consonantal characters both at the beginning of syllables before vowels and at the end of syllables after vowels, for printing vowel sounds of syllables, and for printing numerals, the types used at the beginning of syllables before vowels being S, F, D, T, H, G, K, W, B, P, R, M, L, Y, N; those used at the end of syllables after vowels being R, L, a first S, N, K, M, D, G, P, F, T, B, TH, Z, and a second S; those used for the vowels being Ā, O, OO, A, E, I, Ē, U; and those used for the numerals being 1, 2, 3, 4, 5, 6, 7, 8, 9, 0; the said types used at the beginning of syllables before vowels being arranged in the said machine so that reading from left to right B, F, G, K, and P will print before L and R; S will print before T, F, H, K, P, L, W, M, and N; T will print before H, R, W, and M; D will print before R and W; G, H, and K, will print before

W; and W will print before R, the said types used at the end of syllables, after vowels, being arranged in said machine so that, reading from left to right, R will print before L; both R and L will print before N, K, M, D, F, P, B, G, TH, T, Z, and the second S; the first S will print before K, M, D, P, T, and the second S; N will print before K, D, G, TH, T, Z, and the second S; K will print before D, T, and the second S; M will print before D, P, T, Z, and the second S; D will print before G, TH, Z, and the second S; F will print before TH, T, and the second S; P will print before T and the second S; G will print before TH; B, G, and TH will print before Z and the second S; and T will print before the second S; and the said types for printing the vowels being arranged in said machine so that, reading from left to right, O will print before A, I, and U; A will print before I and U; and I will print before U; and means including a plurality of keys operatively connected to said types for mounting and actuating said types for printing selectively one or more of the said type characters, all of the types used at the beginning of syllables being mounted to print at the left of said vowel types and all of said vowel types being mounted to print at the left of those used at the end of syllables.

39. In a phonetic typewriting machine a set of types for printing the final consonantal sounds of a syllable and comprising characters R, L, a first S, N, K, M, D, G, P, F, T, B, TH, Z, and a second S, a plurality of type bars each having a pair of certain of said type characters thereon, a plurality of type bars each having a single one of certain of said type characters thereon, a plurality of main keys, means to connect each of said main keys with a type bar so as to cause said type bar to move in a predetermined direction when said main key is depressed to print one of said type characters carried by said type bar when said type bar carries a pair of type characters or to print a single type character when said type bar carries a single type character, a plurality of shift keys, each of said shift keys being closely associated with one of said main keys which is connected to one of said type bars carrying a pair of said type characters, so that the shift key may be depressed simultaneously with its associated main key and with a single finger, means connecting each shift key with the type bar connected to the associated main key to shift the direction of movement of the type bar when the shift key and its associated main key are simultaneously depressed, whereby another type character on said type bar is printed, said type characters being arranged in the machine so that, reading from left to right, R will be printed before L; R and L will print before N, K, M, D, F, P, B, G, TH, T, Z, and the second S; the first S will print before K, M, D, P, T, and the second S; N will print before K, D, G, TH, T, Z, and the second S; K will print before D, T, and the second S; M will print before D, P, T, Z, and the second S; D will print before G, TH, Z, and the second S; F will print before TH, T, and the second S; P will print before T, and the second S; G will print

before TH; B, G, and TH will print before Z and the second S; and T will print before the second S.

40. In a phonetic typewriting machine a set of types for printing the final consonantal sounds of a syllable and comprising the type characters, KS, R, L, a first S, SH, N, K, M, V, D, G, P, CH, F, T, B, ST, TH, Z, and a second S, a plurality of type bars each having a pair of said type characters thereon, a plurality of main keys, means to connect each of said main keys, with a type bar so as to cause said type bar to move in a predetermined direction to print one of said type characters carried thereby when said main key is depressed, a plurality of shift keys, each of said shift keys being closely associated with one of said main keys so that the shift key may be depressed simultaneously with its associated main key and with a single finger, means connecting each shift key with the type bar connected to the associated main key to shift the direction of movement of the type bar when the shift key and its associated main key are simultaneously depressed whereby another type character on said type bar is printed, said type characters being arranged on said type bars and said type bars being arranged in the machine so that, reading from left to right, R will print before L; R and L will print before N, K, M, V, D, F, P, SH, B, G, TH, T, Z, CH, ST, and the second S; the first S will print before K, M, D, P, T, and the second S; N will print before K, D, G, TH, T, Z, CH, ST, and the second S; K will print before D, T, and the second S; M will print before D, P, T, Z, and the second S; V will print before Z and the second S; D will print before G, TH, Z, ST, and the second S; F will print before TH, T, and the second S; P will print before T and the second S; SH will print before T, Z, and the second S; KS will print before TH and T; G, CH, B, and TH will print before Z and the second S; G will print before TH and ST; and T will print before the second S.

41. In a phonetic typewriting machine a set of type characters for printing the vowel sounds of a syllable including the characters Ā, O, OO, A, E, I, Ē, and U; a type bar having the characters Ā and O, a second type bar having the characters OO and A, a third type bar having the characters E and I and a fourth type bar having the characters Ē and U, main keys, each of said type bars having a main key operatively connected to it whereby when its key is depressed said type bar is moved to print one of said characters and a shift key operatively connected with it for causing said type bar to move in a different direction when both said main key and said shift key are depressed for causing the other of said characters to print, said type characters being arranged on said type bars so that said main keys will print the characters O, A, I and U, said type bars being arranged in said machine so that O will print before A, I, and U; A will print before I and U; and I will print before U.

J. LEE SWEENEY.
